CLAIM

The ornamental design for a medicine box, as shown and described.

DESCRIPTION

FIG. 1 is a front, right, top perspective view of the medicine box, showing my new design;

FIG. 2 is a rear, left, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is an enlarged view of detail 11 in FIG. 3;

FIG. 12 is an enlarged view of detail 12 in FIG. 4;

FIG. 13 is an enlarged view of detail 13 in FIG. 7;

FIG. 14 is an enlarged view of detail 14 in FIG. 7;

FIG. 15 is an enlarged view of detail 15 in FIG. 8;

FIG. 16 is an enlarged view of detail 16 in FIG. 8;

FIG. 17 is a front, right, top perspective view of its enlarged scale in an alternate configuration;

FIG. 18 is an enlarged view of detail 18 in FIG. 17;

FIG. 19 is a rear, left, bottom perspective view in a detached state; and,

FIG. 20 is an enlarged view of detail 20 in FIG. 19.

The dashed broken lines in the figures are for the purposes of illustrating portions of the medicine box and form no part of the claimed design.

The dash-dot-dash broken lines are for notating enlarged views and form no part of the claimed design.

1 Claim, 20 Drawing Sheets
